Philip George Rice Kennedy*

UNITED STATES PATENT OFFICE.

DAVID A. DECROW, OF NEW YORK, N. Y., ASSIGNOR TO WORTHINGTON PUMP AND MACHINERY CORPORATION, OF NEW YORK, N. Y., A CORPORATION OF NEW YORK.

PUMP OR COMPRESSOR VALVE.

1,408,724.

Specification of Letters Patent. Patented Mar. 7, 1922.

Application filed August 13, 1920. Serial No. 403,239.

To all whom it may concern:

Be it known that I, DAVID A. DECROW, a citizen of the United States, residing at New York city, county of New York, and State of New York, have invented certain new and useful Improvements in Pump or Compressor Valves, fully described and represented in the following specification and the accompanying drawings, forming a part 10 of the same.

This invention relates to valves of the springless type.

It is the especial object of the present invention to provide a valve of this class which 15 shall be simple in construction, durable, highly efficient in operation, and particularly adapted for use in pumps for liquids, although valves of similar construction may be advantageously used in compressors, 20 blowing engines, and like apparatus.

It is a further object of the invention to provide a valve of the class described which, when in normal or closed position, will be held under tension against its seat, and 25 which when opened will be properly supported to prevent deformation of the valve disk, the construction also providing means whereby the pressure fluid will be directed only against the outer portion of the elastic 30 valve disk, thus securing a large flow area with small flexing of the outer portion of the disk and thus securing proper action and long life of the valve.

For a full understanding of the invention, a detailed description of a construction embodying the same in its preferred form will now be given in connection with the accompanying drawings forming a part 40 of this specification, and the features forming the invention then specifically pointed out in the claims.

In the drawings—

Figure 1 is a central section of the valve construction, and

Figure 2 is a top plan view thereof.

As illustrated in the accompanying drawings, the valve construction includes a body 1 forming inlet and outlet ports and circular valve seat 2, and a hub 3 centrally supported by the body 1 by means of arms 4. The upper surface of the hub 3 is slightly concave and below the level of the circular valve seat 2, and positioned thereon is an elastic valve disk 5, preferably of rubber 55 and of a thickness and quality best suited

to the particular use for which the valve is intended. In order that the valve may be properly supported when open, and to prevent the valve disk being flexed back too far with consequent liability to injury, an 60 abutment 6 is provided, having a convex face opposite the valve, but preferably of concavo-convex form, as shown, between which and hub 3 the valve disk 5 is securely held by screw 7.

It will be observed that the valve seat 2 has its edge bevelled or rounded and that the hub 3 is cone-shaped, with its apex toward the inlet, so that the fluid passes through the valve seat and past the valve 70 in substantially a single direction without sharp turns. With this construction, the valve disk will at all times be held under tension on its seat when the valve is closed, due to the concave surface of the hub 3 75 being slightly lower than the circular valve seat 2. The pumped fluid will be guided by the cone shaped hub to exert pressure on the valve disk near its periphery and approximately tangentially to the valve, thereby securing a uniform and easy opening of the valve and flow of the fluid, while the abutment 6, due to its cone shape, will permit full opening of the valve and at the same time prevent its opening so far as to 85 weaken or deform the flexible disk.

What I claim is:

1. A valve for pumps and the like, comprising a valve body forming inlet and outlet ports and a circular valve seat, a cone 90 shaped hub with its apex toward the flow of liquid and its valve supporting surface below the level of the circular valve seat, an elastic valve disk positioned on said hub and adapted to be held under tension on said 95 seat, and an abutment for said valve.

2. A valve for pumps and the like, comprising a valve body forming inlet and outlet ports and a circular valve seat, a hub and supporting arms therefor, said hub having 100 its valve disk supporting surface below the circular valve seat and its opposite end cone shaped to direct the fluid against the outer portion of the disk, a rubber disk valve supported on said hub and adapted to be 105 held under tension on the valve seat, and a convex abutment for the valve disk, the whole being held together by a single screw centrally of the valve and abutment.

3. A valve for pumps and the like, com-

prising a valve body forming inlet and outlet ports and a circular valve seat, a hub having its supporting surface below the circular valve seat, and an elastic valve disk 5 supported on said hub and held under tension on the valve seat, said ports being arranged to direct the flow outward and near the outer edge of the valve disk.

4. A valve for pumps and the like, comprising a valve body, a circular valve seat, a hub and supporting arms therefor, an abut-

ment, a valve disk positioned between the abutment and hub, said hub being so positioned relatively to the valve seat that 15 the valve in its normal position will be held under tension on its seat, and guiding means for directing the flow to the valve outward and near the outer edge of the valve disk.

In testimony whereof, I have hereunto set 20 my hand.

DAVID A. DECROW.
